HENRY J. SCHUMACHER AND FRANK RICE, OF MEADVILLE, PENNSYLVANIA,
ASSIGNORS OF ONE-THIRD TO S. D. PETERSON, OF NEW CASTLE, PENNSYLVANIA.

GAME DEVICE.

1,422,383.

Specification of Letters Patent.

Patented July 11, 1922.

Application filed January 28, 1921. Serial No. 440,579.

To all whom it may concern:

Be it known that we, HENRY J. SCHUMACHER and FRANK RICE, citizens of the United States, residing at Meadville, in the county of Crawford and State of Pennsylvania, have invented new and useful Improvements in a Game Device, of which the following is a specification.

This device is designed to simulate mechanically some features of a game of base ball. Broadly it consists in rotating a bat, delivering a ball to the path of the bat, and providing a chance relation between the rotation and delivery of the ball so that the ball may be hit, or may be missed, or may be delivered in different directions.

The invention is illustrated in the accompanying drawings as follows:

Fig. 1 shows a plan view of the device.
Fig. 2 a bottom view of the device.

Fig. 3 a section on the lines 3—3 in Fig. 1.

Fig. 4 an enlarged view of a securing latch.

1 marks the board, 2 a surrounding shoulder or enclosure, 3 a diamond which is laid out on the board, and 4 spring clips which operate in the game as players, these being located in the positions ordinarily assumed by players in a game of base ball.

5 A bat 5 is fixed on an upright shaft 6 which extends through the board. A gear 7 is fixed on the lower end of the shaft 6. A rack 8 operates on the gear 7, the rack being carried by a rod 9. The front end 35 of the rod is carried by a guide 10 and the rear end is secured to a rod 14, the front end of the rod 14 being carried by a guide 11 on the board. A spring 12 is secured to the rod 9 and to a screw 13 on the under- 40 side of the board and tends to draw the rod to a forward position. In this forward position the rack 8 is out of the gear 7 leaving the shaft free so that the bat may be rotated as a chance device. The rod 14 ex- 45 tends through a guide 15 arranged on the enclosing shoulder or border 2. It is provided with a notch 16 into which a catch 17 drops when the rod is drawn forward. A spring 18 yieldingly forces the latch 17 into 50 the notch.

The forward end of the rod 14 is up- turned through the guide 11 and slot 20 in the board, the upper end of the rod extending forward forming a plunger 21. This 55 plunger is adapted to operate on a ball 22,

the ball being dropped into a depression 23 under the clip in the pitcher's position.

In the operation of the device the rod 14 is drawn outwardly until the latch 17 drops into the notch 16. The ball 22 is put in position under the pitcher's clip. In drawing back the rod 9, the rack 8 moves into mesh with the gear 7 and rotates the bat in a reverse direction slightly. On moving the catch to release position the rods 14 and 9 are snapped forward by the spring 12. The plunger 21 through impact with the ball snaps it forward into the path of the bat as it is rotated. The same forward movement of the rod 9 operating through the rack rotates the bat. If the bat is in the part of its path which is traversed by the ball it will hit the ball giving to the ball a direction incident to the position of the bat at the moment of impact. If the bat is in the part of its path out of the path of the ball, the ball will merely pass through under the catcher's clip. When the rack is moved forward and the bat has been rotated by it the rack moves out of engagement with the gear and the bat continues to rotate as a chance wheel thus varying the point at which it operates with relation to the delivery of the ball with each operation.

Clips 24, 25, 26 and 27 are arranged around the edge of the board and adapted to receive the ball as it moves along the board. It will be understood that these clips are small spring clips so that when the ball moves under them the ball will be engaged and held. The clips 24 covering a wider and more open space may be designated as single-base hits, the clip 25 as two-base hits, the clip 27 as a three-base hit and the clips 26 as home runs, the space through which the ball must travel to get to these clips determining the points.

In playing the game it is played in a manner after the ordinary game of base ball, first one player being at the bat and then the other. Where the ball passes without the impact of the bat and is caught by the clip it operates as a strike. If the bat moves it out of the diamond it operates as a foul and counts as a strike in the manner of the rules of base ball. If the ball is hit by the bat and is received and retained by one of the player clips it is counted an out. On the other hand if the ball passes the players into the clips indicating hits

these are computed as advancing a player who has been at bat.

What we claim as new is:—

1. In a game device, the combination of a mechanically actuated batting means; means for delivering a ball to the batting means; and a chance device cooperating with one of said means varying the operative relation of the batting means and the delivery means 10 to vary the action of the bat on the ball.
2. In a game device, the combination of a chance mechanism; a bat actuated by the chance mechanism; and means for delivering a ball to the bat, said chance mechanism 15 varying the action of the bat to produce a chance variation in the operative relation between the means and the bat.
3. In a game device, the combination of a rotating chance mechanism; a bat actuated by the chance mechanism; and means for delivering a ball to the bat, said chance mechanism varying the action of the bat to produce a chance variation in the operative relation between the means and the bat.
4. In a game device, the combination of a mechanically actuated batting means; means for delivering a ball to the batting means; and a spring actuated chance mechanism cooperating with one of said means and 25 varying the operative relation of the batting means and the delivery means to vary the action of the batting means on the ball.
5. In a game device, the combination of a bat; a shaft on which the bat is mounted; 30 a gear on the shaft; a rack operating on the gear and into and out of mesh with the gear and adapted to rotate the shaft and permit the shaft to spin after the disengagement of the rack from the gear; a plunger 35 actuated with the rack for delivering a ball 40 to the bat; and a spring actuating the plunger and rack.
6. In a game device, the combination of a bat; a shaft on which the bat is mounted; means for operating the shaft to rotate the 45 bat, said means releasing the bat at one extreme of its movement to permit it to operate as a rotating chance device; and means for delivering a ball to the bat.
7. In a game device, the combination of a chance mechanism; a bat actuated by the chance mechanism; and a spring actuated plunger for delivering a ball to the bat, said chance mechanism varying the action of the bat to produce a chance variation in 55 the operative relation between the plunger and the bat.
8. In a game device, the combination of a chance mechanism; a bat actuated by the chance mechanism; means for delivering a ball to the chance mechanism, said mechanism varying the operative relation between said means and said bat; and means for receiving and holding a ball actuated by the bat.
9. In a game device, the combination of a chance mechanism; a bat actuated by the chance mechanism; and means for delivering a ball to the bat, said chance mechanism actuating the bat in relation to the means 65 for delivering a ball to permit the ball in some instances established by chance to pass the bat.

In testimony whereof we have hereunto set our hands.

HENRY J. SCHUMACHER.
FRANK RICE.
